Specification of Letters Patent.

Patented Jan. 1, 1918.

Application filed December 18, 1916. Serial No. 137,491.

To all whom it may concern:

Be it known that we, WILLIAM J. HAMPTON and WILLIAM H. RITTS, citizens of the United States, and residents of Pittsburgh and Etna, respectively in the county of Allegheny and State of Pennsylvania, have invented a new and useful Improvement in Rolling-Mills; and we do hereby declare the following to be a full, clear, and exact description thereof.

Our invention pertains to rolling mills, that is, to mills comprising a plurality of rolls through which a billet of steel is passed successively, thereby to form said billet into an elongated plate or sheet.

Rolling mills of the kind referred to, as now in use, generally consist of a plurality of sets of rolls, there being usually three of such sets, generally known as the "roughing" rolls, the "strand" rolls, and the "finishing" rolls. The set of roughing rolls ordinarily comprises three rolls disposed one above the other, these rolls usually having a plurality of passes arranged one beside the other. In some instances, the strand rolls have two or four passes, one above the other. In other instances, the strand rolls have an odd number of passes depending upon the ultimate direction which it is desired that the billet shall take. Usually, the billet is first carried through the pass between the bottom roughing roll and the center roughing roll, and is then carried back through the pass between the center roughing roll and the upper roughing roll; it is then carried back through a pass, arranged beside the first pass, between the bottom roughing roll and the center roughing roll, and then back through a similar pass between the center roughing roll and the top roughing roll. The four passes between the roughing rolls may be sufficient; but sometimes a billet may go through six passes of these rolls. From the roughing rolls the partly rolled plate is transferred to the strand rolls; and it is carried to and fro between these rolls, in the same way as in the case of the roughing rolls. The nearly finished plate is then transferred to the finishing rolls, through which it is passed once, and then carried on to a suitable shearing device or the like.

It is an object of the present invention to improve generally upon rolling mills broadly of the type referred to above. It is another object of the invention to provide a simple, efficient, and quickly-operating means for changing the direction of the billet after the same has passed through the rolls, thereby to permit it to go back through the rolls in the opposite direction.

It is a further object of the invention to provide a simple, efficient, and quickly-operating means for raising the billet from a position in which it has just come through a lower pass of the rolls, into a position from which it may go through an upper pass of the rolls. It is a further object of the invention to provide an improved means for transferring the billet from a position in which it has gone through an upper pass of the rolls into a position from which it may go through a lower pass of the rolls.

It is still another object of the invention to provide a simple, quickly-operating, and efficient means for changing the direction of movement of the partly finished plate after the same has been carried through a lower pass of a set of rolls, and bring it into a position for going through an upper pass of such set of rolls.

It is a still further object of the invention generally to provide improved means for changing the direction of movement of the billet, in the various stages of its transformation into a finished plate, for transferring it from and to upper and lower passes of any one set of rolls, and for transferring it from one set of rolls to another. And other and further objects of the invention will appear from the following specification taken in connection with the claims annexed thereto.

A rolling mill constructed in accordance with our invention is described, by way of example, in the following specification and is shown in the accompanying drawings. It is especially to be understood, however, that the invention may be embodied in other forms, and that changes may be made in the form described and shown, without exceeding the scope thereof, as defined in the appended claims.

In the drawings:

Figure 1 is a plan of a rolling mill constructed in accordance with our invention;

Fig. 2 is a partial section, on an enlarged scale, taken on the line 2-2 of Fig. 1, looking in the direction of the arrows;

Fig. 3 is a partial section, on an enlarged scale, taken on the line 3-3 of Fig. 4, looking in the direction of the arrows;

Fig. 4 is a partial transverse section, on an enlarged scale, taken on the lines 4-4 of Figs. 1 and 3, looking in the direction of the arrows;

Fig. 5 is a partial section, on an enlarged scale, taken on the line 5-5 of Fig. 1, looking in the direction of the arrows;

Fig. 6 is a partial section, on an enlarged scale, taken on the line 6-6 of Fig. 1, looking in the direction of the arrows;

Fig. 7 is an enlarged detail view, showing the means for actuating the pinch rolls for making the final pass through the roughing rolls, the device being seen as from the line 7-7 of Fig. 1; and

Fig. 8 is an enlarged detail view showing the means for actuating the pinch rolls for effecting the first pass through the strand rolls and the first pass through the finishing rolls, the mechanism being viewed as seen from the line 8-8 of Fig. 1.

Like reference characters refer to like parts throughout the following specification and the several figures of the accompanying drawing.

Referring now particularly to Figs. 1, 2 and 6, A indicates the roughing rolls, supported in the ordinary bearings, and rotated in the usual manner. In the embodiment of our invention now being described, there are three of these roughing rolls, A', A², and A³, respectively. These rolls are formed with three sets of passes, which are indicated on the drawings as a, b, and c, each set comprising an upper pass and a lower pass.

The upper pass c is more constricted than the lower pass c, which latter, in turn, is more constricted than the upper pass b. The passes become, in turn, less constricted, until the lower pass a is reached, which is the least constricted of all. It will be seen that as a billet is carried forward through the lower pass a, backward through the upper pass a, forward through the lower pass b, backward through the upper pass b, forward through the lower pass c, and backward through the upper pass c, it will be rolled out to a lesser thickness at each pass.

Upon leaving the roughing rolls, the partly rolled plate is transferred to the strand rolls B. These strand rolls B comprise three rolls B', B², and B³. In the embodiment now being described the strand rolls are formed with two sets of passes, d and e, each set comprising an upper and a lower pass. The upper pass d is more constricted than the

lower pass d; but the passes e are identical with the passes d, so as to permit the passes e to be used when the rolls are worn at the passes d. The passage of the partly finished plate forward through the lower pass d, and 70 backward through the upper pass d, further elongates the plate and further reduces its thickness. The plate is then transferred to the finishing rolls, which consist of a pair of rolls C disposed one above the other, the 75 plate simply passing forward between these rolls.

At the front side of the machine,—i. e. at the side from which the billet first enters the rolls,—a plurality of feed rolls 10 are 80 mounted upon a suitable supporting structure. These rolls are continuously rotated by a suitable motor and gearing, indicated at 11, such as those heretofore in use in mills of this character. The billet f is removed 85 from the furnace and placed upon the rotating rolls 10, which carry it forward to the lower pass a of the roughing rolls A, the billet being thus seized between the roughing rolls A' and A², and carried 90 through the same, thereby making its first pass.

On the rearward side of the machine there are provided three forwarding rolls 12, 13 and 14, respectively (Fig. 2), which rotate 95 in the same direction as the rolls 10. The roll 12 is placed on a higher plane than the roughing roll A², the roll 13 being likewise placed on a higher plane than the roll 12, and the roll 14 being placed on a higher 100 plane than the roll 13. Thus the rolls 12, 13 and 14, together with inclined intermediate shelves 12^a and 13^a, placed between them, form an inclined guide, up which the billet is carried after passing between the 105 roughing rolls A' and A². Beyond the forwarding rolls 12, 13 and 14 are placed three returning rolls 15, 16 and 17, respectively, which are rotated in the opposite direction to that of the forwarding rolls. The rolls 110 15, 16 and 17 are arranged in the same plane with each other; and a continuation of this plane is formed by a table 18 which has adjustably mounted thereon a support 19 for a spring buffer 20. Placed above the forwarding rolls 12 and 13 are two further returning rolls 21 and 22. The returning rolls 21 and 22 rotate in the same direction as the returning rolls 15, 16 and 17, but are placed upon a higher plane than these last. A 120 shelf 23 is disposed between the returning rolls 21 and 22; and a guide roll 24 is placed immediately in front of the roll 21. The returning rolls 21 and 22, the shelf 23, and the guide roll 24, are all mounted upon a 125 standard 25 suitably supported from the main structure.

After the billet f makes its first pass, through the lower pass a between the roughing rolls A' and A², its front end is carried 130

onto the forwarding roll 12, and thence, over the shelf 12^a, onto the forwarding roll 13. These rolls, with the forwarding roll 14, carry the billet forward in an upwardly inclined direction. Thus the billet will reach a position such as that indicated in full lines in Fig. 2. After the billet has been moved farther forward from the position shown in Fig. 2, its uppermost end will overbalance its lowermost end, permitting its uppermost end to fall upon the returning rolls 15, 16 and 17. The momentum of the billet will carry it forward until it strikes the resilient buffer 20, which will give the billet an impulse in the return direction. The returning rolls 15, 16 and 17, rotating in a direction opposite to that of the forwarding rolls, will cause the billet to move back over the path that it has already traversed, until its end strikes the guide roll 24. (See dotted line position, Fig. 2.) When the billet strikes the guide roll 24, its front end is directed upwardly onto the returning roll 21. The billet *f* is thus carried upward onto the returning rolls 21 and 22, and is thereby directed into the upper pass *a*, between the roughing rolls A' and A³, thereby making its second pass.

After being carried through the upper pass *a*, between the roughing rolls A' and A³, the billet *f* is received upon a transferring device 26 (Figs. 1, 3 and 4). This transferring device consists of a plurality of feet 27, which are secured, by bolts 28, in transverse grooves 29 formed in a plurality of shelves 30, one of which shelves is disposed between each of the feed-rolls 10. The connection of the feet 27 with the shelves 30 is such as to permit of transverse adjustment of the feet with respect to the shelves. Connecting between the feet is an elongated web 31, from which extends upwardly and outwardly an inclined slideway-portion 32. A horizontal shelf-portion 33 projects outwardly from the upper part of the slideway-portion 32, and terminates in a vertical guide-portion 34.

As the billet *f* emerges from the upper pass *a* between the roughing rolls A' and A³, having made its second pass, its front end comes upon the shelf portion 33 of the transferring device 26, as shown in full lines in Fig. 4. The shelf portion 33 is less in width than one-half the width of the billet *f*; so that when the billet has become freed from the roughing rolls, it will fall into the position indicated in dotted lines in Fig. 4, and will thence slide down the slideway-portion 32 onto the feed rolls 10. The billet is thus transferred from the plane of the upper passes of the roughing rolls to the plane of the lower passes of the latter. The upright web 31 of the transferring device 26 also serves as a guide for properly directing the billet, prior to its first pass, into the lower pass *a*.

Upon falling from the transferring device 26 onto the feed rolls 10, the billet is fed forward by these continuously rotating rolls, and is thus directed into the lower pass *b* between the roughing rolls A' and A². Upon being carried through the rolls, thus making its third pass, the billet again rides up the forwarding rolls 12, 13 and 14, overbalances, falls upon the returning rolls 15, 16 and 17, and strikes a second resilient buffer 35 on the table 18, the buffer 35 being situated farther back than the buffer 20, to allow for the increased length of the billet. The buffer 35 gives a returning impulse to the billet, which latter is then carried backward by the returning rolls 15, 16 and 17 onto the returning rolls 21 and 22, which latter feed the billet into the upper pass *b*, between the roughing rolls A' and A³.

Upon emerging from the rolls, having thus made its fourth pass, the billet comes onto a transferring device 26^a, which is of a similar construction to the transferring device 26, and includes an upright web 31^a, a slideway-portion 32^a, a shelf portion 33^a, 90 and a guide portion 34^a. The transferring device 26^a is longer than the transferring device 26, to accommodate the increased length of the billet. In the manner which has been described above in connection with the transferring device 26, the billet is again transferred to the feed rolls 10. The web portion 31^a of the transferring device 26^a forms a guide for properly directing the billet, in its third pass, into the lower pass *b*. Likewise, the guide portion 34^a of the transferring device 26^a operates as a guide for the billet during its emergence, on its second pass, from the upper pass *a*.

Upon the billet *f* being delivered, by the transferring device 26^a, to the continuously rotating feed rolls 10, it is fed, by these rolls, to the lower pass *c*, between the roughing rolls A' and A². The billet is carried through the rolls, thus making its fifth pass. 105 Although still referred to, for convenience, as a billet, the metal has now assumed the shape of an elongated and relatively thin sheet. The billet, in this form, does not have the stiffness which it had in its original 115 shorter form; and it is not desirable further solely to rely upon its mere lying on the forwarding and returning rolls for effecting its forwarding and return movement. For greater certainty of action, therefore, pinch-rolls are provided for moving the billet after the same has perfected its fifth pass.

The pinch-rolls associated with the roughing rolls are shown in Fig. 5. They consist of rolls 36 and 37, mounted one at each end 125 of a balance arm 38. The balance arm 38 is rockably mounted, at its center, on a shaft 39 carried by a stand 40 suitably mounted on the main structure. Depending from the shaft 39 is an arm 40^a, which is connected by 130

a link 41 (Fig. 7) with a head 42 carried by a piston rod 43. The piston of the rod 43 moves in a steam cylinder 44, which is governed by a slide valve contained in a valve chamber 45. The stem 46 of the slide valve is connected, by an arm 47, with a shaft 48 which extends across the machine to the outer side thereof, and there carries an operating lever 49. By shifting the lever 49 in one direction, the side valve is moved to admit steam to the front side of the piston in the cylinder 44. This results in a rearward movement of the piston rod 43, which causes the balance arm 38 to be rocked so as to bring the pinch-roll 36 into operative relation with the forwarding roll 14. By moving the lever 49 in the opposite direction, steam is admitted to the rear side of the piston, and the piston rod 43 is caused to move forward, whereby the balance arm 38 is made to rock in the opposite direction, to bring the pinch-roll 37 into operative relation with the returning roll 16. A man is stationed at the lever 49, to operate the pinch-rolls as each billet comes to them through the lower pass *c* of the roughing rolls.

Upon the billet *f* being transferred, from the transferring device 26^a, to the continuously rotating feed rolls 10, these latter present it to the lower pass *c*, between the roughing rolls A' and A². The billet is carried through these rolls, thereby making its fifth pass, and rides up the forwarding rolls 12, 13 and 14. As soon as the front end of the billet reaches the forwarding roll 14, the lever 49 is operated to cause the pinch-roll 36 to descend upon the billet and hold it firmly against such forwarding roll. (See full lines Fig. 5.) The forwarding roll 14, with the billet thus forcibly clamped against it, is able thereafter to continue the forwarding movement of the billet. As soon as the rear end of the billet reaches the pinch-roll 36, the lever 49 is operated to cause the pinch-roll 37 to descend upon the billet and hold it firmly against the returning roll 16. When this happens, the returning roll 16, having the billet thus firmly clamped against it, will cause the latter to move in the opposite direction and be carried up onto the returning rolls 21 and 22 (see dotted lines Fig. 5). The returning rolls 21 and 22 present the billet to the upper pass *c*, between the roughing rolls A' and A³, between which rolls it is carried, thereby completing its sixth pass.

As the billet emerges from the upper pass *c*, between the roughing rolls A' and A³, it is received upon a table 50, the latter being supported upon the ends of a plurality of transverse rails 51. These rails 51 are carried by a pair of I-beams 52, supported by the main structure. The table 50 is provided along its edge with an upright guide

53, which serves to guide the billet as it comes out from the upper pass *c*, and also serves to guide the opposite edge of the billet as it comes out from the upper pass *b* on completing its fourth pass.

When the billet reaches the table 50, the operations upon it have been completed, so far as the roughing rolls are concerned. The billet has the form of an elongated, relatively thin strip, which, being white hot, is quite flexible. The operations of the roughing rolls have been described as consisting of six passes. However, this may be varied. For instance, only four passes may be used, the billet being carried twice to and fro between the roughing rolls. When only four passes are used, the pinch-rolls will ordinarily be employed prior to the fourth pass.

The rails 51 extend across the machine from the roughing rolls A to the strand rolls B. These rails terminate in downwardly inclined portions 54, forming a sloping surface, the lower ends of these downwardly inclined portions 54 terminating at a feed table 55 placed in the front of the strand rolls B. Extending diagonally across one side of the machine, at the end of the receiving table 50, is a plate 56 having, at its outer edge, an upwardly-extending guide 57. After the billet has come out onto the receiving table 50, from the upper pass *c* of the roughing rolls, it is manually pulled across the rails 51 and allowed to slide down the slope formed by the inclined portions 54. In this way the billet is brought onto the feed table 55 for the strand rolls. The inclined guide wall 57 of the plate 56 assists in this transfer.

A longitudinal guide 57^a is provided upon the feed table 55, and is placed in such a position that when the billet is pulled against it, the billet will be in proper position for entering the lower pass *d* between the strand rolls B' and B². The top surface of a feed roll 58 extends through the feed table 55, this feed roll rotating in such a direction as to cause the billet to be moved toward the strand rolls. With the feed roll 58 co-operates a pinch roll 59 which is moved down, to press the billet against the roll 58, as soon as the billet is brought into position upon the feed table 55. The means for operating this pinch roll 59 will be described below. As soon as the billet has been brought upon the feed table 55, and the pinch roll 59 has been operated, to force the billet into close engagement with the feed roll 58, this latter roll causes the billet to move forward into the lower pass *d*, between the strand rolls B' and B². The billet is then carried through these strand rolls, thus effecting its seventh pass.

Upon being carried through the lower pass *d* of the strand rolls, the billet emerges

upon an upwardly inclined table 60, which is carried upon I-beams 61 supported from the main structure of the machine. Beyond the end of the table 60 there are provided a 5 forwarding roll 62 and a pair of returning rolls 63 and 64. With the forwarding roll 62 and the returning roll 64 coöperate a pair of pinch rolls 65 and 66, the same being mounted upon a balance arm 67, which is 10 operated by a device which is similar to the device described in connection with pinch rolls 36 and 37, the same being controlled by an operating lever 68, placed beside the operating lever 49 so that the same work- 15 man can attend to the operation of both levers. Hingedly connected with a transverse shelf 69 connected across the uprights of the frame work of the strand rolls B is a chute plate 70. This chute plate is flared out- 20 wardly from its upper to its lower end and is provided with upwardly extending side members 71, thereby properly to receive the billet, in the return movement of the latter, and direct it to the upper pass *d* between the 25 strand rolls B' and B³. Likewise the table 60 is provided with an upright guide 72 for directing the billet properly to and from the pinch rolls.

As the billet comes out onto the table 60, 30 and as soon as its end reaches the forwarding rolls 62, the workman operates the lever 68 in such a way as to cause the pinch roll 65 to descend upon the billet and grip it firmly against the forwarding roll 62. In 35 coming to the forwarding roll 62, the billet forces its way under the chute plate 70, lifting the latter somewhat about its pivot in its hinged connection with plate or shelf 69. When the rear end of the billet has 40 passed beyond the end of the chute plate 70, the workman operates the lever 68 in such a way as to cause the pinch roll 66 to grip the billet against the returning roll 64, whereby a reversal of the direction of movement of the billet is effected. Upon this 45 reversal of movement taking place, the billet travels back again down the table 61, but, when moving in the new direction, its end rides up the chute plate 70 and is thereby 50 directed to the upper pass *d* between the strand rolls B' and B³. The billet is then carried through these strand rolls, thereby effecting its eighth pass.

In order to permit the second pair of 55 passes *e* to be used in place of the first pair of passes *d*, when the latter become worn, the chute plate 70 is mounted upon the support 69, in such a manner that it can be easily moved from one side of such support, 60 in which it coöperates with the passes *d* of the strand rolls, to the other side of the support, in which it coöperates with the passes *e* of the strand rolls. The guides 57^a and 72 are likewise movable; and the pinch 65 rolls 65 and 66 are wide enough to accommo-

date the billet through which ever pair of passes it is being carried. When the passes *d* become worn, all that is necessary is to shift the guides 57^a and 72, and move the chute plate 70 to the other side of the support 69. 70

As the billet emerges from the upper pass *d* of the strand rolls, it comes upon a table 73 which extends diagonally across the machine from a position in line with the strand 75 rolls to a position in line with the finishing rolls C. This table is of a sectional nature and is provided with a vertical guide flange 74 along its inner edge. Extending from the table 73 are transverse rails 75, terminating in inclined portions 76, these rails being of a similar nature to the rails 51, with their inclined portions 54, described above. The inclined portions 76 of the rails 75 terminate upon a feed table 77 which is disposed in 80 alignment with the finishing rolls C.

Upon the billet, now in the form of a very long and thin plate, emerging from the upper pass *d* onto the table 73 it is manually pulled across the rails 75 and down the inclined portions 76, onto the feed table 77. The upper surface of the feed roll 58 projects through the table 77 in the same way as it projects through the table 55, and with this feed roll coöperates a pinch roll 78, 95 which may be brought down into engagement with the billet to press the latter against the feed roll. When the pinch roll 78 is thus brought into engagement with the billet, the feed roll moves the billet forward 100 between the finishing rolls C, through which it is carried, thus making its ninth pass. Upon emerging from the finishing rolls C, the billet comes upon a roll table 79, from which it is carried to a suitable shearing 105 device.

The means for operating the pinch rolls 59 and 78 is shown in Fig. 8. Taking the pinch roll 78, this roll is mounted upon an arm 80 carried by a rockable shaft 81. The 110 shaft 81 is connected, by means of a crank 82 and link 83 with a head 84 mounted on the rod 85 of a piston 86. The piston 86 reciprocates in a steam cylinder 87, which is governed by a slide valve 88. The slide valve 88 115 is connected by means of a link 89 with an operating lever 90. When the operating lever 90 is in the position shown in the figure, the piston 86 will be forced to the rear of the cylinder, thereby moving the 120 crank 82 backward, and lifting the pinch roll 78 out of operative relation with the feed roll 58. When the operating lever 90 is shifted into its opposite position, the steam will be admitted behind the piston 86, 125 thereby forcing the latter, and its rod 85, forward and causing the pinch roll 78 to descend into operative relation with the feed roll 58. The mechanism for operating the pinch roll 59 is the same as that which has 130

just been described for operating the pinch roll 78, and is governed by an operating lever 91. In practice, a workman will be assigned to these pinch rolls; and he can operate either the lever 91, for the pinch roll 59, or the lever 90 for the pinch roll 78, in accordance with the position of the billets in the machine.

The rolling mill described above is particularly advantageous in that it permits of a continuous movement of the billet from the time the latter is placed onto the original feed rolls until after it passes the finishing rolls. Special elevating devices, requiring to be operated individually for each billet, for lifting the billet from the plane of the lower rolls to the plane of the upper rolls, are done away with; and in this way the speed at which the machine can operate is greatly increased. Likewise, the necessity of personal supervision at the various stages of the operation is considerably reduced. A further advantage of the device is that the jolting of the billets, especially at the times when they fall from the upper plane to the lower plane, owing to the action of the transferring devices 26 and 26^a results in a loosening of the scale permitting the scale to fall away from the billets to a large extent.

Having thus fully described our invention, what we claim as new and desire to secure by Letters Patent is:

1. In a rolling mill, the combination with a set of rolls comprising three rolls having a pass between the lower pair and a pass between the upper pair, of a device for changing the direction of movement of the billet coming through the lower pass and causing it to return through the upper pass, said device including forwarding rolls, returning rolls beyond said forwarding rolls, other returning rolls disposed above said forwarding rolls, and a buffer disposed beyond said first-named returning rolls.

2. In a rolling mill, the combination with a set of rolls comprising three rolls having a pass between the lower pair and a pass between the upper pair, of a device for changing the direction of movement of the billet coming through the lower pass and causing it to return through the upper pass, said device including forwarding rolls, returning rolls beyond said forwarding rolls, other returning rolls disposed above said forwarding rolls, guide rolls for directing the billet to the second-named returning rolls, and a buffer disposed beyond said first-named returning rolls.

3. In a rolling mill, the combination with a set of rolls comprising three rolls having a pass between the lower pair and a pass between the upper pair, of a device for changing the direction of movement of the billet coming through the lower pass and causing it to return through the upper pass,

said device including forwarding rolls, returning rolls beyond said forwarding rolls, other returning rolls disposed above said forwarding rolls, and a longitudinally adjustable resilient buffer disposed beyond said first-named returning rolls.

4. In a rolling mill, the combination with a set of rolls comprising three rolls having a pass between the lower pair and a pass between the upper pair, of a device for changing the direction of movement of the billet coming through the lower pass and causing it to return through the upper pass, said device including a forwarding roll co-operating with the pass of said lower pair of rolls, a returning roll co-operating with the pass of said upper pair of rolls, and another returning roll beyond said forwarding roll and located on a horizontal plane between the horizontal planes of said forwarding roll and said first-named returning roll.

5. In a rolling mill, the combination with a set of rolls comprising three rolls having a pass between the lower pair and a pass between the upper pair, of a device for changing the direction of movement of the billet coming through the lower pass and causing it to return through the upper pass, said device including a forwarding roll co-operating with the pass of said lower pair of rolls, a returning roll co-operating with the pass of said upper pair of rolls, another returning roll beyond said forwarding roll and located on a horizontal plane between the horizontal planes of said forwarding roll and said first-named returning roll, and a buffer disposed beyond said second-named returning roll.

6. In a rolling mill, the combination with a set of rolls comprising three rolls having a pass between the lower pair and a pass between the upper pair, of a device for changing the direction of movement of the billet coming through the lower pass and causing it to return through the upper pass, said device including a forwarding roll co-operating with the pass of said lower pair of rolls, a returning roll co-operating with the pass of said upper pair of rolls, another returning roll beyond said forwarding roll and located on a horizontal plane between the horizontal planes of said forwarding roll and said first-named returning roll, and a guide roll for directing the billet to said first-named returning roll.

7. In a rolling mill, the combination with a set of rolls comprising three rolls having a pass between the lower pair and a pass between the upper pair, of a device for changing the direction of movement of the billet coming through the lower pass and causing it to return through the upper pass, said device including a forwarding roll co-operating with the pass of said lower pair of rolls, a returning roll co-operating with

the pass of said upper pair of rolls, another returning roll beyond said forwarding roll and located on a horizontal plane between the horizontal planes of said forwarding roll 5 and said first-named returning roll, a longitudinally adjustable resilient buffer disposed beyond said second-named returning roll, and a guide roll for directing the billet from said second-named returning roll to 10 said first-named returning roll.

8. In a rolling mill, the combination with a set of rolls comprising three rolls having a pass between the lower pair and a pass between the upper pair, of a device for 15 changing the direction of movement of the billet coming through the lower pass and causing it to return through the upper pass, said device including a plurality of forwarding rolls coöperating with the pass of said 20 lower pair of rolls, said forwarding rolls being disposed in an upwardly extending plane, a returning roll beyond said forwarding rolls, means for directing the billet from said returning roll to the pass between 25 said upper pair of rolls, and a buffer disposed beyond said returning roll.

9. In a rolling mill, the combination with a set of rolls comprising three rolls having a pass between the lower pair and a pass 30 between the upper pair, of a device for changing the direction of movement of the billet coming through the lower pass and causing it to return through the upper pass, said device including a plurality of forwarding rolls coöperating with the pass of 35 said lower pair of rolls, said forwarding rolls being disposed in an upwardly extending plane, a returning roll disposed above said forwarding rolls, a returning roll disposed beyond said forwarding rolls, and a 40 buffer beyond said second-named returning roll.

10. In a rolling mill, the combination with a set of rolls comprising three rolls having 45 a pass between the lower pair and a pass between the upper pair, of a device for changing the direction of movement of the billet coming through the lower pass and causing it to return through the upper pass, 50 said device including a plurality of forwarding rolls coöperating with the pass of said lower pair of rolls, said forwarding rolls being disposed in an upwardly extending plane, a returning roll disposed above 55 said forwarding rolls, a returning roll disposed beyond said forwarding rolls, means for guiding the billet from said second-named to said first-named returning roll, and a longitudinally adjustable resilient 60 buffer beyond said second-named returning roll.

11. In a rolling mill, the combination with a set of rolls comprising three rolls having a 65 pass between the lower pair and a pass between the upper pair, of a device for chang-

ing the direction of movement of the billet coming through the lower pass and causing it to return through the upper pass, said device including means for moving the billet forward from the said lower pair of 70 rolls to a higher plane, means for moving the billet into said upper pair of rolls, and means, disposed intermediate the horizontal planes of said first and second-named means, for directing the billet to said second-named 75 means.

12. In a rolling mill, the combination with a set of rolls comprising three rolls having a pass between the lower pair and a pass between the upper pair, of a device for 80 changing the direction of movement of the billet coming through the lower pass and causing it to return through the upper pass, said device including means for moving the billet forward from the lower pair of rolls 85 to a higher plane, means, disposed above said first-named means, for moving the billet into said upper pair of rolls, and means, disposed intermediate the horizontal planes of said first- and second-named means, for 90 directing the billet to said second-named means.

13. In a rolling mill, the combination with a set of rolls comprising three rolls having a pass between the lower pair and a 95 pass between the upper pair, of a device for changing the direction of movement of the billet coming through the lower pass and causing it to return through the upper pass, said device including continuously rotating 100 means for moving the billet forward from the lower pair of rolls to a higher plane, means, disposed above said first-named means, for moving the billet into said upper pair of rolls, and continuously rotating 105 means, disposed intermediate the horizontal planes of said first- and second-named means, for directing the billet to said second-named means.

14. In a rolling mill, the combination with a set of rolls comprising three rolls having a pass between the lower pair and a pass between the upper pair, of a device for changing the direction of movement of the billet coming through the lower pass and 115 causing it to return through the upper pass, said device including a forwarding roll, a second forwarding roll beyond the first, a returning roll beyond said second forwarding roll, a second returning roll above said 120 first forwarding roll, a pair of movable pinch rolls coöperating with said second forwarding roll and said first returning roll respectively, according to the positions to which said pinch rolls are moved, and means 125 for operating said pinch rolls.

15. In a rolling mill, the combination with a set of rolls comprising three rolls having a pass between the lower pair and a pass between the upper pair, of a device for 130

changing the direction of movement of the billet coming through the lower pass and causing it to return through the upper pass, said device including a forwarding roll, a **5** returning roll beyond said forwarding roll, a second returning roll above said forwarding roll, and a pinch roll movable into and out of operative relation with said first returning roll.

In testimony whereof, we, the said **WIL- 10**
LIAM J. HAMPTON and **WILLIAM H. RITTS**,
have hereunto set our hands.

WILLIAM J. HAMPTON.
WILLIAM H. RITTS.

Witnesses:

J. N. COOKE,
A. D. P. MILLER.
